(57) **CLAIM**

The ornamental design for a hair curling appliance as shown and described.

DESCRIPTION

FIG. 1 is a bottom front perspective view of an ornamental design for a hair curling appliance according to the present invention;

FIG. 2 is a right side elevational view of the hair curling appliance of FIG. 1;

FIG. 3 is a left side elevational view of the hair curling appliance of FIG. 1;

FIG. 4 is a front elevational view of the hair curling appliance of FIG. 1;

FIG. 5 is a rear elevational view of the hair curling appliance of FIG. 1;

FIG. 6 is a top plan view of the hair curling appliance of FIG. 1; and,

FIG. 7 is a bottom plan view of the hair curling appliance of FIG. 1.

The broken lines shown in FIGS. 1-7 are for the purpose of illustrating portions of the hair curling appliance, which form no part of the claimed design.

1 Claim, 5 Drawing Sheets
